UNITED STATES PATENT OFFICE

IRVEN E. COFFEY, OF SANTA ANA, CALIFORNIA

STORAGE BATTERY INSPECTION LAMP

Application filed February 13, 1931. Serial No. 515,549.

My invention relates to a storage battery inspection lamp, the purpose of which is to have a small lamp illuminated by the electric current from a storage battery which may be connected between the opposite terminals or poles of any one of the cells of a multiple cell battery, and the lamp positioned to shine the light either in the battery filling opening to observe the level of the acid solution therein or to observe a reading on a hydrometer or other instruments such as a volt meter or ammeter.

Another object and feature of my invention is having the lamp pivotally mounted on conductor legs which are adapted to engage the opposite poles of a battery cell whereby the lamp with a suitable reflector may be swung, for instance, on a horizontal axis in reference to these conducting legs and, hence, position the lamp at any desired suitable point to give the proper illumination.

Another object and feature of my invention is the construction of a support or a lamp mounting attached to the conductor legs whereby the electric current from these legs will be conducted from the two contacts of the lamp, one of these contacts usually being on the screw threaded exterior and the other on the terminal end of the lamp.

My invention is illustrated in connection with the accompanying drawing, in which:

Fig. 1 is a perspective view of my invention as applied to the storage battery with the lamp housing tilted;

Fig. 2 is a side elevation taken in the direction of the arrow 2 of Fig. 3, partly broken away;

Fig. 3 is a side elevation taken in the direction of the arrow 3 of Fig. 2 with the lamp housing partly broken away;

Fig. 4 is a partial bottom view taken in the direction of the arrow 4 of Fig. 2.

In constructing my invention I employ two conducting legs 11 and 12, which are formed of strips of metal. These have gripping jaws 13 at the bottom which are formed of lower and upper sections 14 and 15, these being preferably curved as indicated in Fig. 4, and sharpened on the edge 16 to engage

the opposite poles 17 and 18 of a battery designated at 19.

The lamp housing 20 has two side straps or pieces 21 and 22 and a top section 23 which is illustrated as being formed integral with the side 21. These sides are formed channel shaped, each having a web portion 24 and marginal flanges 25. The lower portions 26 have the flanges removed and are connected to the conducting legs by pivot rivets 27, these pivots being diametrically opposite and in horizontal alignment when the device is located as indicated in Fig. 1. The top 23 is also channel shaped and has an end portion 28.

Attached to the side strap 22 there is a reflector 29 illustrated as being curved with the concave side turned toward the pivoting line of the legs on the lamp housing. This has a conducting lamp socket 30 formed therein. An insulating strip 31 is placed on top of this reflector and engages the marginal or flange edges of the top 23. The top and the reflector are secured together by bolts 32, which bolts have insulating bushings 33, thus insulating the top 23 from the reflector 29. This top has a slight bulged section 34 which engages with the end contact 35 of the lamp bulb, the socket 30 engaging the screw threaded section 36 of the lamp bulb.

By this construction the legs may have the jaws 13 mounted on the battery engaging the sides of the battery poles which face each other, and as these legs are formed of a spring metal with a vertically outward bend, due to the rigidity of the side straps and of the lamp housing in general, give a firm support. The rivets are sufficiently tight to give a frictional resistance to the rotation of the lamp housing on the legs so that the housing may be tilted into various positions in reference to the legs. For instance, it may be tilted to a position at right angles to the legs as illustrated in Fig. 1 or in alignment with the legs as illustrated in Figs. 2 and 3, or at any intermediate angle. The lamp housing may be thus positioned to project the light from the lamp through the filler 37 of the battery cell and thus show the height of the acid solution in the battery, or the lamp housing may

be positioned, for instance, as shown in Fig. 1, to illuminate the scale on the hydrometer used in testing the battery for the specific gravity of the solution. It is obvious that the light may be shifted for use on any of the cells of the battery and thus each individual cell may be readily illuminated for tests. Usually, however, a single mounting in the center is sufficient to illuminate all of the cells of a three cell battery. It is also obvious that the device may be used to illuminate the scale on electrical instruments, such as volt meters and ammeters.

One of the features in making the jaws 13 with upper and lower sections and having these concave is to enable good contacts to be made with the terminals of different cells of a battery or with the terminals of one of the cells and a battery pole, either 20 the prongs at the ends of the curve cutting into the material of the battery terminal or the sharpened edges forming this connection. In addition, the feature of having the upper and lower sections gives a two point 25 connection for each of the legs and supports these legs with sufficient rigidity to hold the lamp housing in any adjusted position.

Various changes may be made in the details of construction without departing from the spirit or scope of the invention as defined 30 by the appended claims.

I claim:

1. A storage battery inspection lamp comprising in combination a lamp housing having a lamp mounted therein and with depending side straps, a leg pivotally connected to each side strap by aligned pivots, each leg being resilient and having a jaw at its lower end, the said jaws on account of their 35 resilient legs tending to move outwardly and adapted to grip a battery terminal and form a support for the housing, each leg and each side strap forming an electrical connection, and a connection from each side strap to the opposite terminals of the lamp.

2. A storage battery inspection lamp as claimed in claim 1, one of the side straps having a concave reflector connected thereto with a lamp positioned in the center of such 50 reflector.

3. A storage battery inspection lamp comprising in combination a lamp housing having a pair of side straps, each strap having a top section, one positioned below the other, the top 55 sections and the side straps being insulated one from the other, said top sections forming a support and electrical connection for the electric lamp, each side strap having a pivot, the pivots being in axial alignment, and each pivot having a resilient leg frictionally connected thereto, each leg having an outwardly extending jaw with sharpened gripping edges to engage a battery terminal.

4. A storage battery inspection lamp as 60 claimed in claim 3, the jaws having distinct

upper and lower sections spaced apart, and each section having a concave curve with sharpened points on the ends of the curve.

5. A storage battery inspection lamp having a pair of jaw structures with sharpened edges, legs having a resilient mounting connected to said jaws adapted to force the sharp edges into contact with battery terminals, said connection being adapted to support the legs, and a lamp connecting device attached to the legs, such legs forming opposite connections to the lamp mounting. 70

6. A storage battery inspection lamp comprising a pair of legs, such legs having jaw structures at the bottom, said jaw structures 75 being flat at their under surface and adapted to rest on the top of a battery cell and thereby support the legs, the jaws having sharpened points to engage and form an electrical contact with the battery terminals, the legs forming opposite electrical connections, and a lamp operatively connected to said legs. 80

7. A storage battery inspection lamp having a lamp housing, a pair of resiliently mounted legs connected thereto, each leg having a jaw-like structure extending outwardly therefrom and having sharpened outer edges, the jaws being flat on the bottom and adapted to support the legs and housing on the upper surface of a battery cell, the legs being stressed to press the jaws outwardly into contact with battery terminals, said legs forming opposite electrical connections to the 85 housing. 90

In testimony whereof I have signed my name to this specification.

IRVEN E. COFFEY.
